UNITED STATES PATENT OFFICE.

WILLIAM L. SPOON, OF COBLE TOWNSHIP, ALAMANCE COUNTY, NORTH CAROLINA.

BALE AND BALE-TRUNK.

963,955.

Specification of Letters Patent. Patented July 12, 1910.

Original application filed October 24, 1896, Serial No. 609,902. Divided and this application filed September 10, 1901. Serial No. 74,985.

To all whom it may concern:

Be it known that I, WILLIAM L. SPOON, a citizen of the United States, residing at Coble township, in the county of Alamance and State of North Carolina, have invented 5 a new and useful Improvement in Bales and Bale-Trunks of Fibrous Material, of which the following is a specification, reference being had to the accompanying drawing.

10 My invention relates particularly to the baling of cotton and similar fibrous materials which have relatively high commercial values and require to be well preserved from the time and place of harvesting to the time 15 and place of use in mill or factory. The most important of these fibrous materials is cotton.

My improved bale is a "round" or cylindrical bale having characteristics to be hereinafter described.

20 In the forming of my bale, the cotton is taken continuously, in small quantities (a thin sheet-form stream), from a loose or unorganized mass of cotton and formed, organized, or fabricated into a bat or sheet of 25 substantial continuity and uniformity of thickness, and in organizing the sheet and applying it, the fibers are more or less "paralleled" and "drawn" or intertwined. And 30 such sheet is made quite thin. And the operation of forming or organizing said sheet or bat varies gradually in rapidity from one edge of the sheet to the other, such variation being from substantially zero at one margin 35 or edge to the maximum rapidity at the opposite edge. On account of such variation in rapidity, the sheet assumes a spiral form, with one edge directed toward the axis of the spiral. Such operation, as a whole, results 40 in forming, organizing or fabricating a thin, spiral sheet, of substantial continuity and even thickness from edge to edge and from end to end and having its fibers paralleled and drawn or intertwined. For convenience, said sheet is hereinafter termed a 45 "spiral sheet", and the stream of fibers from which said sheet is formed is termed a "sheet-spiral" stream. If the rapidity of formation at one edge of the sheet approximates zero, said edge will extend approximately 50 to the axis of the spiral. Said edge may be termed the inner or "axial" edge, and the opposite edge may be termed the outer or "peripheral" edge. And as the 55 sheet is being so formed and organized, it is

preferably subjected to an initial or preliminary compression, whereby it is made dense and the air is expelled, and, subsequent to such initial compression, said sheet is, preferably, kept under tension, for the maintenance of such compression and exclusion of air and for the further "drawing" of the fiber and for the placing of the sheet or bat upon the forming bale or bale-trunk under tension. For the forming of the bale 60 (or bale-trunk which may be severed into sections constituting bales), the convolutions of said spiral sheet are, as fast as the sheet is formed, laid closely or densely against each other by suitable pressure, the axial 65 edge of the sheet extending approximately to the axis of the bale and the peripheral edge of the sheet extending to the perimeter of the bale. And the sheet is preferably laid against the preceding mass, increment by 70 increment, in such manner and with such pressure as to at once attain the full density which it is sought to impart to the completed bale. For convenience in description, such density may be termed "complete" 75 density. Usually "complete" density should be approximately the highest density which the cotton can endure without injury. As already stated, the bat or sheet is preferably given an initial compression for the attainment of density and expression of air. When this is done, on being laid against the end of the bale-trunk the pressure required 80 for the final compression to attain "complete" density, may be much reduced on account of such initial compression. 85

As already indicated, the spiral sheet is progressively applied to or built upon the end of the forming bale or bale-trunk. Hence the bale may be termed an "end-formed" or "end-built" bale. 95

For a form of press adapted to make my improved bale and bale-trunk, I refer to my application Serial No. 609,902, filed in the United States Patent Office, October 24, 1896, of which application this application is a division. 100

In the accompanying drawings, Figure 1 is a perspective view of a portion of the spiral sheet used in forming my bales; Fig. 2 is an edge elevation of a single convolution of said spiral sheet; Fig. 3 is the same convolution in obtuse conical form; Fig. 4 illustrates the same convolution in less obtuse conical form; Fig. 5 is a side elevation of a 110

bale-trunk embodying my improvement; Fig. 6 is an elevation of the left hand or forming end of the bale-trunk shown in Fig. 5; Fig. 7 is a sectional side elevation 5 of a bale severed from the right hand end of the bale-trunk shown by Fig. 5; Fig. 8 is an end elevation of the bale shown by Fig. 7; Fig. 9 is an elevation of the forming end of a bale-trunk which is being formed by 10 the simultaneous application of two spiral sheets or bats; Fig. 10 is a perspective view of sections of such two spiral sheets.

Since the nature of my bale may be best understood by considering the method of 15 forming it, such method will be further described by reference to the drawings.

In Fig. 1 of the drawings, a spiral sheet or bat of which the bale is formed is illustrated in perspective, and Figs. 2, 3, 4, and 20 5 illustrate the placing of such sheet in the bale-trunk. The sheet is always placed at an angle to the axis of the bale-trunk (which is also the axis of the spiral sheet). It may 25 be most readily placed at an angle of approximately 90 degrees to said axis as shown in Fig. 2. To form Figs. 2, 3, and 4, a single convolution of the sheet is cut from the section of the sheet shown by Fig. 1. Such convolution is substantially a circular disk 30 whose radius equals the width of the spiral sheet. Such a disk-form section, if arranged at an angle of substantially 90 degrees to the axis of the bale-trunk, would stand as shown in Fig. 2. But if said angle is to be 35 less than 90 degrees, the section would change from disk-form to obtuse, conical form, the edges, A, B, of said section overlapping, as shown by Fig. 3. And it will be observed that the diameter of the base of 40 such cone will be less than the diameter of the disk form of the section was. If said angle is to be still less, the section is formed into a cone which is still less obtuse, the edges, A, B, overlapping to a greater extent. 45 And it will be observed that this will still further reduce the diameter of the base of the cone. In the bale-trunk shown in Fig. 5, the angle of the sheet and the diameter of the cone are still further reduced. And it 50 will now be apparent, that, for a bat or sheet of a given width, the diameter of the bale-trunk varies with the angle which the sheet sustains to the bale-trunk axis. In these several gradations, illustrated by Figs. 1, 2, 55 3, 4, and 5, the sheet is the same in organization, nature, and dimensions. It is the identical sheet in different positions. And in laying the sheet, the final compression is always perpendicular to the sheet, as indicated by the arrows, so that when the angle 60 of the layer is changed, the direction of the final pressure is correspondingly changed. Any inclination of the sheet will answer if it is intended to maintain the form of the 65 bale only by external mechanical means—

bands or other stays. Indeed, for this purpose, an angle of approximately 90 degrees is, perhaps, the best, for then the stays need be so applied as to act in only one direction, namely lengthwise of the bale. But I have 70 found it desirable to so construct the bale as to adapt it to resist expansion. In other words, I have found it preferable to place the sheet or bat at such an angle to the axis of the bale-trunk as to cause each convolution to bear upon or bind a number of preceding convolutions, whereby the bale is made "self-binding." In such form, the convolutions become conical—strictly speaking, conoidal, nearly conical—and said conoidal convolutions or layers are nested closely 75 within each other. The attainment of such result is facilitated by the laying of the forming bat upon the end of the bale-trunk under tension as well as pressure. Not only 80 does such tension increase the self-binding characteristic, but it makes possible the attainment of complete density with less final pressure than would be needed if such density were to be attained by pressure 85 alone. This self-binding form of the bale is shown in Figs. 5, 6, 7, 8, and 9 of the drawings. And, as above indicated, the fibers in the spiral sheet are to a large extent "drawn" parallel, and intertwined, this 90 result being accomplished by the operation described in my aforesaid application; and when it is desired to make the bale self-binding, the spiral sheet is also under tension. 95

From the completed end of the bale-trunk—the end opposite the end to which the forming bat or sheet is applied—sections of proper length to constitute bales are severed periodically by cutting in a plane to 100 which the bale-trunk axis is perpendicular. And in so severing the bale-trunk, the spiral sheet is cut slantwise, so as to leave a tapering end in the sheet at each side of the cut, wherefore each severed section or bale is 105 composed of a sheet which is tapering at each end, or the bale is composed of convolutions or layers of the sheet; the end layers being tapering in form. 110

The completed bale-trunk or bale may 115 be surrounded by any suitable extraneous binding or wrapping material or means for the sake of preserving the structure of the bale and for the sake of keeping the fibrous material of the bale from being bruised 120 and soiled during handling or storage. I prefer to apply to such bale-trunk or bale a covering of cloth, C, as shown in Figs. 5 and 7, the cloth being an elongated sheet extending spirally and under tension, with the 125 meeting edges overlapping, around the bale-trunk or bale.

I claim as my invention:

1. A bale of fibrous material composed of nested, self-binding layers. 130

2. A bale of fibrous material composed of nested self-binding layers, the layers at each end being tapering in form.
3. As an article of manufacture, a bale of fibrous material composed of a thin, spiral sheet of such material, said sheet being substantially continuous and of uniform thickness and the axial edge thereof extending approximately to the axis of the bale and the peripheral edge thereof extending to the perimeter of the bale, and the sheet being oblique to the bale axis, so that the convolutions of the sheet are of conoidal form and nested, substantially as described.
4. As an article of manufacture, a bale of fibrous material composed of a thin, spiral sheet of such material, said sheet being substantially continuous and of uniform thickness and the axial edge thereof extending approximately to the axis of the bale and the peripheral edge thereof extending to the perimeter of the bale, and the sheet being oblique to the bale axis, so that the convolutions are of conoidal form and nested, and said convolutions being closely compressed against each other and approximately free from air, substantially as described.
5. As an article of manufacture, a bale of fibrous material composed of a thin, spiral sheet of such material, the fibers being paralleled or drawn and said sheet being substantially continuous and of uniform thickness and the axial edge thereof extending approximately to the axis of the bale and the peripheral edge thereof extending to the perimeter of the bale, and the sheet being oblique to the bale axis so that the convolutions of the sheet are of conoidal form and nested, substantially as described.
6. As an article of manufacture, a bale of fibrous material composed of a thin, spiral sheet of such material, the fibers being paralleled or drawn, and said sheet being substantially continuous and of uniform thickness and the axial edge thereof extending approximately to the axis of the bale and the peripheral edge thereof extending to the perimeter of the bale, and the convolutions being conoidal and compressed against each other and under tension, substantially as described.
7. As an article of manufacture, a bale of fibrous material composed of a thin, spiral sheet of such material, said sheet being substantially continuous and of uniform thickness and the axial edge thereof extending approximately to the axis of the bale and the peripheral edge thereof extending to the perimeter of the bale, and the sheet being at such angle to the bale axis and under such tension as to render the convolutions of the sheet nested and the bale self-binding, substantially as described.
8. As an article of manufacture, a bale of fibrous material composed of a plurality of parallel, thin, spiral sheets of such material, each of said sheets being substantially continuous and of uniform thickness and the axial edge thereof extending approximately to the axis of the bale and the peripheral edge thereof extending to the perimeter of the bale, and each such sheet being oblique to the bale axis, so that the convolutions of the sheet are of conoidal form and nested, substantially as described.
9. As an article of manufacture, a bale of fibrous material composed of a plurality of parallel, thin, spiral sheets of such material, each of said sheets being substantially continuous and of uniform thickness and the axial edge thereof extending approximately to the axis of the bale and the peripheral edge thereof extending to the perimeter of the bale, and such sheets being oblique to the bale axis so that their convolutions are conoidal and nested, and said sheets being closely compressed against each other and approximately free from air, substantially as described.
10. As an article of manufacture, a bale of fibrous material composed of a plurality of parallel, thin, spiral sheets of such material, the fibers being paralleled or drawn, and each such sheet being substantially continuous and of uniform thickness inclined to the bale axis and the axial edge thereof extending approximately to the axis of the bale and the peripheral edge thereof extending to the perimeter of the bale, and said sheets being compressed against each other, substantially as described.
11. As an article of manufacture, a bale of fibrous material composed of a plurality of parallel, thin, spiral sheets of such material, the fibers being paralleled or drawn, each of said sheets being substantially continuous and of uniform thickness and the axial edge thereof extending approximately to the axis of the bale and the peripheral edge thereof extending to the perimeter of the bale, and the convolutions of said sheets being conoidal and compressed against each other and under tension, substantially as described.
12. As an article of manufacture, a bale of fibrous material composed of a plurality of parallel, thin, spiral sheets, each of said sheets being substantially continuous and of uniform thickness and the axial edge thereof extending to the axis of the bale and the peripheral edge thereof extending to the perimeter of the bale, and said sheets being at such angle to the bale axis and under such tension as to render the convolutions of the sheet nested and the bale self-binding, substantially as described.
13. As an article of manufacture, a bale of fibrous material composed of a thin, spiral sheet of such material, said sheet being substantially continuous and of uniform

thickness and the axial edge thereof extending approximately to the axis of the bale and the peripheral edge thereof extending to the perimeter of the bale, and the sheet 5 being oblique to the bale axis, so that the convolutions of the sheet are of conoidal form and nested, and an extraneous binding member, substantially as described.

14. As an article of manufacture, a bale 10 of fibrous material composed of a thin, spiral sheet of such material, said sheet being substantially continuous and of uniform thickness and the axial edge thereof extending approximately to the axis of the bale and 15 the peripheral edge thereof extending to the perimeter of the bale, and the sheet being oblique to the bale axis, so that the convolutions are of conoidal form and nested, and said convolutions being closely compressed 20 against each other and approximately free from air, and an extraneous binding member, substantially as described.

15. As an article of manufacture, a bale of fibrous material composed of a thin, spiral 25 sheet of such material, the fibers being paralleled or drawn and said sheet being substantially continuous and of uniform thickness and the axial edge thereof extending approximately to the axis of the bale and the 30 peripheral edge thereof extending to the perimeter of the bale, and the sheet being oblique to the bale axis so that the convolutions of the sheet are of conoidal form and nested, and an extraneous binding member, 35 substantially as described.

16. As an article of manufacture, a bale of fibrous material composed of a thin, spiral sheet of such material, the fibers being paralleled or drawn, and said sheet being substantially continuous and of uniform thickness and the axial edge thereof extending approximately to the axis of the bale and the peripheral edge thereof extending to the 40 perimeter of the bale, and the convolutions 45 being conoidal and compressed against each other and under tension, and an extraneous binding member, substantially as described.

17. As an article of manufacture, a bale of fibrous material composed of a thin, spiral 50 sheet of such material, said sheet being substantially continuous and of uniform thickness and the axial edge thereof extending approximately to the axis of the bale and the peripheral edge thereof extending to the 55 perimeter of the bale, and the sheet being at such angle to the bale axis and under such tension as to render the convolutions of the sheet nested and the bale self-binding, and an extraneous binding member, substantially as described.

18. As an article of manufacture, a bale of fibrous material composed of a plurality of parallel, thin, spiral sheets of such material, each of said sheets being substantially con-

tinuous and of uniform thickness and the 65 axial edge thereof extending approximately to the axis of the bale and the peripheral edge thereof extending to the perimeter of the bale, and each such sheet being oblique to the bale axis, so that the convolutions of 70 the sheet are of conoidal form and nested, and an extraneous binding member, substantially as described.

19. As an article of manufacture, a bale of fibrous material composed of a plurality of 75 parallel, thin, spiral sheets of such material, each of said sheets being substantially continuous and of uniform thickness and the axial edge thereof extending approximately to the axis of the bale and the peripheral 80 edge thereof extending to the perimeter of the bale, and such sheets being oblique to the bale axis so that their convolutions are conoidal and nested, and said sheets being closely compressed against each other and 85 approximately free from air, and an extraneous binding member, substantially as described.

20. As an article of manufacture, a bale of fibrous material composed of a plurality of 90 parallel, thin, spiral sheets of such material, the fibers being paralleled or drawn, and each such sheet being substantially continuous and of uniform thickness inclined to the bale axis and the axial edge thereof extending approximately to the axis of the bale and the peripheral edge thereof extending to the perimeter of the bale, and said sheets being compressed against each other, and an extraneous binding member, substantially as 100 described.

21. As an article of manufacture, a bale of fibrous material composed of a plurality of parallel, thin, spiral sheets of such material, the fibers being paralleled or drawn, 105 each of said sheets being substantially continuous and of uniform thickness and the axial edge thereof extending approximately to the axis of the bale and the peripheral edge thereof extending to the perimeter of 110 the bale, and the convolutions of said sheets being conoidal and compressed against each other and under tension, and an extraneous binding member, substantially as described.

22. As an article of manufacture, a bale 115 of fibrous material composed of a plurality of parallel, thin, spiral sheets, each of said sheets being substantially continuous and of uniform thickness and the axial edge thereof extending to the axis of the bale and the 120 peripheral edge thereof extending to the perimeter of the bale, and said sheets being at such angle to the bale axis and under such tension as to render the convolutions of the sheet nested and the bale self-binding, and 125 an extraneous binding member, substantially as described.

23. A bale of fibrous material composed

of nested, self-binding layers, and an extraneous binding member, substantially as described.

24. A bale of fibrous material composed of nested, self-binding layers, the layers at each end being tapering in form, and an extraneous binding member, substantially as described.

25. As an article of manufacture, a bale of fibrous material composed of a thin, spiral sheet of such material, said sheet being substantially continuous and of uniform thickness inclined to the bale axis, and the axial edge thereof extending approximately 15 to the axis of the bale and the peripheral edge thereof extending to the perimeter of the bale, and the convolutions of said sheet being closely compressed against each other, and an extraneous binding member extending 20 spirally around the bale, substantially as described.

26. As an article of manufacture, a bale of fibrous material composed of a thin, spiral sheet of such material, said sheet being substantially continuous and of uniform thickness inclined to the bale axis, and the axial edge thereof extending approximately 25 to the axis of the bale and the peripheral edge thereof extending to the perimeter of the bale, and the convolutions of said sheet being closely compressed against each other 30 and approximately free from air, and an extraneous binding member extending spirally around the bale, substantially as described.

27. As an article of manufacture, a bale of fibrous material composed of a thin, spiral sheet of such material, said sheet being substantially continuous and of uniform 40 thickness and the axial edge thereof extending approximately to the axis of the bale and the peripheral edge thereof extending to the perimeter of the bale, and the sheet being oblique to the bale axis, so that the 45 convolutions of the sheet are of conoidal form and nested, and an extraneous binding member extending spirally around the bale, substantially as described.

28. As an article of manufacture, a bale of fibrous material composed of a thin, spiral sheet of such material, said sheet being substantially continuous and of uniform thickness and the axial edge thereof extending approximately 50 to the axis of the bale and the peripheral edge thereof extending to the perimeter of the bale, and the sheet being oblique to the bale axis, so that the convolutions are of conoidal form and nested, and said convolutions being closely 55 compressed against each other and approximately free from air, and an extraneous binding member extending spirally around the bale, substantially as described.

29. As an article of manufacture, a bale of

fibrous material composed of a thin, spiral 65 sheet of such material, the fibers being paralleled or drawn and said sheet being substantially continuous and of uniform thickness and the axial edge thereof extending approximately to the axis of the bale 70 and the peripheral edge thereof extending to the perimeter of the bale, and the sheet being oblique to the bale axis so that the convolutions of the sheet are of conoidal form and nested, and an extraneous binding member 75 extending spirally around the bale, substantially as described.

30. As an article of manufacture, a bale of fibrous material composed of a thin, spiral 80 sheet of such material, the fibers being paralleled or drawn, and said sheet being substantially continuous and of uniform thickness and the axial edge thereof extending approximately to the axis of the bale 85 and the peripheral edge thereof extending to the perimeter of the bale, and the convolutions being conoidal and compressed against each other and under tension, and an extraneous binding member extending spirally around the bale, substantially as 90 described.

31. As an article of manufacture, a bale of fibrous material composed of a thin, spiral sheet of such material, said sheet being substantially continuous and of uniform thickness and the axial edge thereof extending approximately to the axis of the bale and the peripheral edge thereof extending to the perimeter of the bale, and the sheet being at 95 such angle to the bale axis and under such tension as to render the convolutions of the sheet nested and the bale self-binding, and an extraneous binding member extending spirally around the bale, substantially as 100 described.

32. As an article of manufacture, a bale of fibrous material composed of a plurality of parallel, thin, spiral sheets of such material, each of said sheets being substantially continuous and of uniform thickness and the 110 axial edge thereof extending approximately to the axis of the bale and the peripheral edge thereof extending to the perimeter of the bale, and each such sheet being oblique to the bale axis, so that the convolutions of the sheet are of conoidal form and nested, and an extraneous binding member extending spirally around the bale, substantially as 115 described.

33. As an article of manufacture, a bale of 120 fibrous material composed of a plurality of parallel, thin, spiral sheets of such material, each of said sheets being substantially continuous and of uniform thickness and the axial edge thereof extending approximately 125 to the axis of the bale and the peripheral edge thereof extending to the perimeter of the bale, and such sheets being oblique to

the bale axis so that their convolutions are conoidal and nested, and said sheets being closely compressed against each other and approximately free from air, and an extraneous binding member extending spirally around the bale, substantially as described.

34. As an article of manufacture, a bale of fibrous material composed of a plurality of parallel, thin, spiral sheets of such material, 10 the fibers being paralleled or drawn, each of said sheets being substantially continuous and of uniform thickness and the axial edge thereof extending approximately to the axis of the bale and the peripheral edge 15 thereof extending to the perimeter of the bale, and the convolutions of said sheets being conoidal and compressed against each other and under tension, and an extraneous binding member extending spirally around the bale, substantially as described.

35. As an article of manufacture, a bale of fibrous material composed of a plurality of parallel, thin, spiral sheets, each of said sheets being substantially continuous and 25 of uniform thickness and the axial edge thereof extending to the axis of the bale and the peripheral edge thereof extending to the perimeter of the bale, and said sheets being at such angle to the bale axis and under such

tension as to render the convolutions of the 30 sheet nested and the bale self-binding, and an extraneous binding member extending spirally around the bale, substantially as described.

36. A bale of fibrous material composed 35 of highly-compressed layers inclined to the bale axis superposed one upon the other in the form of a continuous spiral, and an extraneous binding member extending spirally around the bale, substantially as described. 40

37. A bale of fibrous material composed of nested, self-binding layers, and an extraneous binding member extending spirally around the bale, substantially as described.

38. A bale of fibrous material composed 45 of nested, self-binding layers, the layers at each end being tapering in form, and an extraneous binding member extending spirally around the bale, substantially as described.

In testimony whereof I affix my signature, 50 in presence of two witnesses, this sixteenth day of August, in the year one thousand nine hundred and one.

WILLIAM L. SPOON.
